UNITED STATES PATENT OFFICE.

ROBERT J. FENNELLI, OF NEW YORK, N. Y., ASSIGNOR, BY MESNE ASSIGNMENTS, TO VICTOR X RAY CORPORATION, OF CAMBRIDGE, MASSACHUSETTS, A CORPORATION OF NEW YORK.

DENTIST'S RECORD-HOLDER.

1,361,703.

Specification of Letters Patent.

Patented Dec. 7, 1920.

Application filed June 24, 1918, Serial No. 241,722. Renewed October 27, 1920. Serial No. 419,992.

To all whom it may concern:

Be it known that I, ROBERT J. FENNELLI, a citizen of the United States, residing at Bronx, in the county of New York and 5 State of New York, have invented certain new and useful Improvements in Dentists' Record-Holders; and I do declare the following to be a full, clear, and exact description of the invention, such as will enable 10 others skilled in the art to which it appertains to make and use the same.

This invention relates to dentists' record holders, and it relates more particularly to a combined radiograph holder and verbal 15 record blank.

One object of this invention is to provide a convenient and practical means whereby the radiographic record of a tooth or teeth is always adjacent to the verbal record or 20 written record relating to the tooth or teeth.

Another object is to provide a dentist's record sheet which is constructed to hold the radiograph and written record in a manner to protect both of these forms of rec- 25 ord.

Another object is to provide a record holder of this character in which the radiograph is visible while in its normal protect- 30 ed position in engagement with the protect- ing sheet.

Another object is to provide a radiograph holder or photograph holder which permits inspection of both sides of the radiograph or photograph while the latter is held by 35 the holder, and which permits free access of light through the radiograph or photograph from either side while thus held.

Other objects and advantages may become 40 apparent to persons who read the following details of description in connection with the accompanying drawings, in which:

Figure 1 is a perspective view of my im- 45 proved dentist's record holder in its open position;

Fig. 2 is a view of the same in its closed position;

Fig. 3 is a detail view of a slotted trans- 50 parent sheet which holds a radiograph or the like;

Fig. 4 is a sectional view along the line 4-4 of Fig. 2; and

Fig. 5 is a perspective view showing the radiograph being held by the transparent sheet shown in Fig. 3.

Referring to the drawings in detail, in 55 which similar reference characters corre- spond with similar parts throughout the several views, this record holder comprises an opaque sheet 7, a second opaque sheet 8 and a transparent sheet 9, the radiograph 60 being indicated by the numeral 10.

The sheet 7 is provided with an opening or window 11 which is covered by the transparent sheet 9 and the latter is provided with W-shaped slits 12 which receive the 65 corners, respectively, of the radiograph film 10, so as to hold this radiograph film se- 70 curely while protecting the major portion of one side thereof by means of the middle portion of the transparent sheet. In order 75 that the transparent sheet may be securely and permanently held over the opening 11, without interfering with placing the films in engagement with the transparent sheet, I provide the opaque sheet 8 with an open- 80 ing 13 which registers with the opening 11 of the opaque sheet 7, and I secure the edge portions of the opaque sheet 8 to the sheet 7 by any appropriate means, such means 85 being preferably employed also for secur- ing the edge portions of the transparent sheet between sheets 7 and 8. It will be seen, therefore, that when the film or radio- 90 graph is held by the transparent plate, the same may be observed or inspected through 95 the transparent sheet; but if a more care- ful and thorough inspection is desired, the inspection may be made from the opposite side, that is, from the side which is unpro- 100 tected by the transparent sheet.

Sheet 7 is provided with a fold-line or hinge 14 approximately at its middle por- 105 tion, so as to divide the sheet 7 into two rec- ord sections one of which is imperforate and forms a protecting flap; one of these 110 sections containing the radiographic record de- 120 scribed in the foregoing, and the other section containing printed words 15, abbreviations, etc., which refer to blank spaces 16, these blank spaces being opposite the 125 said words respectively and being adapted to receive a written record or complement of the words 15—for instance, the name of the patient whose teeth are depicted by the 130 radiograph 10, the address of such patient, 135 the diagnosis of his dental condition, etc.

In Fig. 1 the inner surfaces of the record holder are visible, and it will be seen that

when the sheet 7 is folded along the line 14, and these inner surfaces are brought into contact with one another, the otherwise exposed surface of the film 10 is now protected by the inner surface of the printed and written record, while the latter is protected by the inner surfaces of the film and sheet 8.

- 10 A securing flap 17 may be provided on one of the sections of the sheet 7, and a slit 18 may be provided in the other section for receiving the flap 17, whereby the record holder may be secured in its closed position as shown in Fig. 4.
- 15 The back of one of the sections of the sheet 7 may be provided with words, abbreviations and blanks, as indicated at 19, for convenience in filing the record holder.

Although I have described this embodiment of my invention very specifically, it is to be understood that this invention is not limited to these exact details, but I am entitled to make minor changes without departing from the scope of the inventive idea disclosed in the foregoing description and following claims.

What I claim as my invention is:

1. A record holder comprising a sheet having a window therethrough and having 30 a fold-line which provides a protecting flap, a transparent sheet having its edges secured to the first said sheet at the margin of said window and having its middle part closing said window, and a picture on said transparent sheet and having one side protected thereby and having its other side normally protected by the said flap, the latter being normally turned on the fold-line so as to lie over and protect the other side of said picture, said picture being visible from either side of said window when the sheet is unfolded.

2. A record holder comprising a sheet having a window therethrough and having thereon a verbal record of a person and of 45 an object relating to that person, said sheet having a fold-line between said window and verbal record to provide a protecting flap, said protecting flap containing said verbal record, a transparent sheet having its edges secured to the first said sheet at the margin of said window and having its middle part closing said window, and a picture of said object secured to said transparent sheet and having one side protected thereby and having its other side normally protected by said protecting flap, the latter being normally turned on said fold-line so as to lie over and protect the other side of said picture and also protect the verbal record, said picture 60 being visible from either side of said window when the sheet is unfolded.

3. A record holder comprising an opaque sheet having an opening therethrough and having a plurality of blank record spaces 65 and words indicating the subjects to be written in said record spaces, said sheet also having a fold-line between said opening and record spaces; a transparent sheet closing said opening and provided with means to secure thereto the corners of a transparent sheet containing a photograph; and a third sheet, the latter having an opening registering with the first said opening, said third sheet having its edges secured to the first 75 said sheet and co-operating with the latter to hold said transparent sheet.

In testimony whereof I have hereunto set my hand.

ROBERT J. FENNELL.
